TABLE MOVING DOLLY

George C. Ireland, Akron, Ohio

Application April 20, 1950, Serial No. 157,135

6 Claims. (Cl. 214—383)

1

This invention relates to a dolly.

The invention is more particularly concerned with an improved form of dolly for moving tables from one position to another in restaurants, club rooms or the like.

As is generally known, it is a common and essential practice to move tables in a lunch room or club room preparatory to cleaning up operations or for making room for parties or the like following lunch and at which time the tables are orderly positioned about the room.

The usual lunch table is comparatively heavy and accordingly requires the expenditure of considerable manual energy in clearing a floor of a relatively large lunch or club room by the now common practice of individually grasping the tables and carrying them to an out-of-the-way position.

It is accordingly a primary object of this invention to provide a dolly by use of which tables may readily be transported from one position to another with the expenditure of minimum manual effort.

A further object of the invention is to provide a table transporting dolly which functions as a table lifting jack and a table transporting carriage.

A still further object of the invention is to provide a dolly which is capable of transporting different forms and sizes of tables.

A still further object of the invention is to provide a table transporting dolly which is durable, easy to operate and which is capable of being stored in a relatively small space.

Other objects and advantages of the invention will become apparent in the course of the following detailed description, taken in connection with the accompanying drawings, wherein:

Fig. 1 is a side elevational view of the improved dolly in an inoperative position.

Fig. 2 is a top plan view of the dolly.

Fig. 3 is a rear elevational view of the dolly with the upper portion thereof broken away.

Fig. 4 is an enlarged view showing one end of the movable table top clamping jaw in elevation and the adjacent end of the operating handle in section.

Fig. 5 is an enlarged sectional view showing the adjustable table leg supporting arm.

Fig. 6 is a side elevational view of the dolly in table grasping position.

Fig. 7 is a view similar to Fig. 6 but showing the dolly in table transporting position.

Referring now in detail to the drawings, 10 designates an elongated base which is preferably

provided by a cylindrical rod in loop form and which rod is preferably tubular to provide lightness in construction. A plate 11 is secured to the lower side of the base adjacent each end thereof and each plate is provided with an inverted U-shaped bracket 12 in which is rotatably journaled a wheel or coaster 13.

A U-shaped tubular member of rubber or other cushioning material 14 is supported on each end 10 of the base 10 for a purpose later to appear.

A pair of parallel laterally spaced tubular members 15 are disposed transversely of base 10 and intermediate the ends thereof. The members 15 terminate at their forward ends adjacent the front edge of the base and the rear ends thereof are disposed substantially rearwardly of the rear edge of the base.

A plate 16 is rigidly supported on the lower sides of members 15 adjacent the rear ends thereof. An inverted U-shaped bracket 17 is rigidly supported by the plate and a wheel or coaster 18 is rotatably journaled in the bracket.

The axes of the wheels 13 are spaced a greater distance from the axes of members 15 than is the axis of wheel 18 for a purpose later to appear.

A linearly adjustable table supporting arm is provided and which is formed as a continuation of the members 15, the arm accordingly being at right angles to the base and projecting forwardly thereof.

30 The said arm comprises a pair of tubular members 19 having their rear ends telescopically engaged in the front ends of tubular members 15 and suitable set screws 20 are provided to retain the members 19 in adjusted position. A pair 35 of cylindrical rods 21 have their rear ends telescopically engaged in the front ends of members 19 and suitable set screws 22 are provided to retain the rods in adjusted position.

40 A flexible table leg engaging boot 23 in the form of a tube is supported on a unitary connection 24 between the front ends of rods 21 for a purpose later to appear.

45 A pair of upright bars 25 extend vertically upward from base 10 and such bars are retained in spaced relation by suitable spacing blocks 26 (Fig. 3) which may be disposed at suitable intervals along the bars. The lower ends of the bars are rigidly supported on a plate 27 which in turn is rigidly secured to the bottom side of base 10 (Fig. 2).

50 A pair of brace bars 28 extend from plates 11 to opposite sides of the bars 25 at points spaced substantially above the base 10.

55 A rigid table top gripping jaw 29 is provided

as integral lateral extensions from the upper ends of bars 25.

A plate 31 is disposed beneath jaw 29 and such plate is provided with a screw 32 projecting rigidly upward therefrom. The screw extends through a block 33 disposed between the spaced bar portions of jaw 29 and a thumb nut 34 engages the upper edge of the block and cooperates with the screw to draw the block firmly in engagement with the lower side of jaw 29.

This structure provides for replacement of the plate 31 or the substitution therefor of other plates of different thicknesses.

A movable jaw 35 is pivotally supported by a cotter pin 36 between the bars 25 and intermediate the ends of the jaw.

While the heights of tables from the floor to the top surfaces thereof are substantially standard, no adjustment of the fixed jaw is necessary but since the thickness of table tops vary, provision is made for adjustment of the movable jaw 35. For this purpose the bars 25 are provided with a series of vertically spaced apertures 37 for selectively receiving the pin 36.

The jaw 35 is also provided with a plate 38 opposed to plate 31 and each of such plates is preferably provided with a pad 39 to prevent marring of the tables when handling same by the dolly.

The dolly further includes an operating handle 40 provided with a suitable terminal hand gripping portion 41.

A connection is provided between adjacent ends of the jaw 35 and the handle 40 whereby the handle may optionally be placed in operating position or allowed to dangle vertically as in Fig. 1 for conservation of storage space as well as to avoid possible personal injury by the projecting handle.

Such connection preferably comprises a tongue 42 on the rear end of jaw 35 and which is provided with a slot 43 which terminates forwardly of the rear end of the tongue. The adjacent end of handle 40 is provided with a recess 44 which opens through the lower edge of the handle and a pivot pin 45 is carried by the handle and extends through the slot 43 and the recess 44.

With this construction, the handle in Fig. 1 need only be raised into parallelism with jaw 35 and then pushed forwardly to the position of Fig. 4, in which position lateral movement of the handle will impart swinging movement to the jaw.

Having set forth the preferred structure of the dolly, the operation is as follows:

The handle 40 is raised and pushed forwardly to provide a vertical rigid connection with the jaw 35. The dolly is moved toward the table T (Fig. 6) with the arm 19, 21 and the jaws 29 and 35 horizontally disposed and with the dolly being supported on the front wheels 13 only, with the rear wheel disposed above and in spaced relation to the floor f. The dolly is advanced toward the table to a position wherein the boot 23 engages the pedestal p and the jaws 29 and 35 receive an edge of the table top t therebetween. It is of course to be understood that the arm 19, 21 has been properly adjusted for the particular size tables to be transported.

With the dolly in the table engaging position of Fig. 6, downward pressure is exerted on the handle 40 which results in the dolly pivoting about the axes of wheels 13 until wheel 13 engages the floor as shown in Fig. 7.

The table is raised off the floor in this jack-like action of the dolly and upon forward pushing on lever 40 the table may readily be transported to a desired location, after which the downward pressure on handle 40 is released and the table engages the floor with the dolly in the position of Fig. 6. The handle 40 may then be pulled rearwardly and dropped down to the position of Fig. 1 in the event that no further tables are to be moved.

When it is desired to move four-legged tables, two of the legs will engage the cushioning members 14 on base 16 and the tables may otherwise be moved, as above described.

While I have disclosed my invention in accordance with a single structural embodiment thereof, such is to be considered as illustrative only, and not restrictive, the scope of the invention being defined in the subjoined claims.

What I claim and desire to secure by U. S. Letters Patent is:

1. A table transporting dolly comprising an elongated substantially horizontal base, supporting wheels journaled beneath said base, a pair of spaced bars projecting upwardly from said base and terminating in lateral portions providing a table top engageable fixed jaw, a movable table top engageable jaw beneath the fixed jaw and pivoted intermediate its ends between said bars, and an adjustable table column engageable arm extending from said base in the direction of said jaws.

2. The structure according to claim 1, wherein said wheels comprise a wheel adjacent each end of said base with their axes in the plane of said bars, and a single wheel disposed rearwardly of said bars and in a plane intermediate the planes of the first wheels, the wheels all being of uniform diameter with the axis of the last wheel closer to the base than the axes of the first two wheels.

3. The structure according to claim 1, wherein said adjustable arm comprises two pairs of laterally spaced telescoping members, and a table column engageable boot supported by the outermost pair of said members.

4. The structure according to claim 1, wherein said arm is disposed centrally of said base, and a pair of reinforcing rods extending from points adjacent the ends of said base to said bars at points thereon substantially spaced from said base.

5. The structure according to claim 1, together with a cushioning member on each end of said base.

6. The structure according to claim 1, together with an operating handle having a pivotal and interlocking connection with said movable jaw.

GEORGE C. IRELAND.
